UNITED STATES PATENT OFFICE.

ALBERT BAUMGARTEN, OF FREEPORT, ILLINOIS.

DESIGN FOR A BASE FOR NUT-CRACKERS.

SPECIFICATION forming part of Design No. 30,227, dated February 21, 1899.

Application filed January 28, 1899. Serial No. 703,738. Term of patent 7 years.

To all whom it may concern:

Be it known that I, ALBERT BAUMGARTEN, a citizen of the United States of America, residing at Freeport, in the county of Stephenson and State of Illinois, have invented a certain new and original Design for a Base for Nut-Crackers, of which the following is a specification.

My invention relates to a certain new and original design for a base for nut-crackers.

This design is illustrated in the drawing by means of a perspective view, the main portion of the base A being a substantially flat and comparatively long raised portion, from 15 which projects a laterally-extending tapered lug B, and from the opposite ends of which project downward legs C D.

The characteristic features of this design are comprised in a base for nut-crackers having the substantially flat raised portion A, provided with the laterally-extending finger B, and having at its opposite ends the downwardly-projecting legs C D. 20

I claim as new and desire to secure by Letters Patent--

The design for a base for nut-crackers, substantially as shown and described. 25

ALBERT BAUMGARTEN.
